UNITED STATES PATENT OFFICE.

ROBERT EMMET KEOUGH, OF MONTREAL, QUEBEC, CANADA.

RAILROAD-FROG.

1,389,144.

Specification of Letters Patent. Patented Aug. 30, 1921.

Application filed July 21, 1920. Serial No. 398,032.

To all whom it may concern:

Be it known that I, ROBERT E. KEOUGH, of the city of Montreal, Province of Quebec, Dominion of Canada, a subject of the King of Great Britain, have invented certain new and useful Improvements in Railroad-Frogs; and I do hereby declare that the following is a full, clear, and exact description thereof.

10 My invention relates to frogs for all manner of switches and of crossings where frogs are required, its application being universal. The invention has for its object to obtain more bearing surface for the wheel opposite the point of the frog and a frog having a greater throat with smaller channel.

To this end the invention consists of a railway frog comprising a point and wing-rails, each of the latter being bent to present an inwardly offset portion, thus presenting channels of minimum width at each side of the point. More specifically stated the invention consists of a frog the wing-rails of which are bent to present knees 25 forming a greater throat portion between such wing-rails and expanding from the knees toward the point in order to present an inwardly offset wheel supporting portion and a channel having a gradual taper 30 extending beyond the point of the frog, the wing rails having also portions running parallel to the sides of the point and the inner portions of these wing rails are bent to incline outwardly away from the point. Another feature of the invention consists in 35 forming each of the wing rails with a rise opposite the point, or in cases where the frog is built up and not cast the point is lowered. The idea in connection with the cast 40 feature is to prevent the wheels striking the point and breaking it down due to the taper of the M. C. B. car-wheel tread. Consequently I aim to compensate for the taper of the wheel by a difference in level between 45 the point and off-set portions of the wing rails.

For full comprehension, however, of my invention reference must be had to the accompanying drawings in which similar reference characters indicate the same parts and wherein:

Figure 1 is a plan view of a built up frog constructed according to my invention;

Fig. 2 is a transverse sectional view taken 55 on line 2—2 Fig. 1;

Fig. 3 is a transverse sectional view taken on line 3—3 Fig. 1;

Fig. 4 is a sectional view taken on line 4—4 Fig. 1;

Fig. 5 is a longitudinal sectional view 60 taken on line 5—5 Fig. 1;

Fig. 6 is a similar view to Fig. 1 and illustrating a cast frog;

Fig. 7 being a sectional view in line 7—7 65 Fig. 6; and

Fig. 8 a longitudinal sectional view taken on line 8—8 Fig. 6.

The rails the juncture of which form the point in the built-up frog are indicated at *b* and *c* and the point at *d*. The point-rails 70 are laid in the usual way; and the wing-rails have particular form imparted to them for the purpose of the invention. These wing-rails are the same in all respects excepting that one is a right hand and the other a left 75 hand rail. Each wing is bent to present three obtuse angles or knees *e*, *f* and *g*, one leg *h* of which lies parallel to the adjacent side of the point and is spaced comparatively close to this side of the point, sufficient 80 space (indicated at *i*) and no more being left to present a channel to accommodate the wheel-flange. The leg *j* of each wing-rail presents what is known as the guard side of the wing-rail and extends from the throat of 85 the frog to a point adjacent the frog point where it joins the leg *h*, its angular relation with the latter not being very marked. This presents the guards in the locations necessary to accommodate wheels having flanges 90 stipulated by M. C. B. specifications. The knee *g* is located a greater distance from the apex of the point than has been the practice in the past, in other words these knees are located nearer the toe of the frog, the effect 95 being that a greater throat with narrower channel is produced. This particular location of the knee *g* reduces its angle and practically eliminates the side thrust, the wheels entering the channel also called 100 "flange-wag" of the frog through the throat. The legs *h* of these wing-rails lie in obtuse angular relation with the legs *j* and are spaced to meet the other rails of the switch in the usual way.

In order to demonstrate more clearly the manner in which the point and wing-rails of my improved frog should be laid or cast and their particular relative angular arrangement, I have illustrated in Fig. 1 the 110

frog as heretofore employed in dotted lines in conjunction with my improved frog.

The advantage of my frog over those heretofore used is that more bearing for the 5 tread of the wheel is provided in the vital part of the frog and the point which suffers most and heretofore has carried the wheels almost entirely, is relieved. This is owing to the fact that minimum distance to accom- 10 modate the flanges of the standard M. C. B. wheels is provided between the point and the leg *h* of the wing-rails, the particular angular relation of the leg *j* to this leg *h* being such that the nearer approach of the throat 15 to the toe of the frog, presents as above mentioned a greater throat with which the narrow channel communicates by an entrance tapered from the throat to the channel.

20 What I claim is as follows:

1. A railway frog comprising a point and wing-rails each presenting a leg extending from the throat of the frog to within close proximity of the point and lying at an angle 25 to a side of the point and a contiguous leg lying parallel to such side of the point pre-

senting a relatively great throat and diminished channel for the purpose of relieving the point.

2. In a railway frog the combination with 30 a point, of wing-rails each bent to produce three obtuse angles or knees and legs between the knees and extending toward the toe and heel of the frog, one of such legs extending from a point inward from the apex 35 of the point of the frog and obliquely beyond the latter to present a relatively great throat and terminate in the leg extending to the toe of the frog, the leg forming a continuation of the opposite end of this oblique 40 leg being disposed parallel to the side of the frog, such last mentioned parallel leg joining another leg obliquely arranged relatively to the side of the point of the frog.

In testimony whereof I have signed my 45 name to this specification in the presence of two witnesses.

ROBERT EMMET KEOUGH.
